UNITED STATES PATENT OFFICE.

AUBREY LAWRENCE COLLINS, OF LONDON, ENGLAND.

STAY OR STRUT FOR HINGED LIDS OF GRAMOPHONE AND OTHER CABINETS.

Application filed December 15, 1927, Serial No. 240,294, and in Great Britain January 25, 1927.

This invention relates to improvements in stays or struts for hinged lids of gramophone and other cabinets.

The invention has for its object the production of an automatic support or strut which is simple in construction quiet in action, and which does not require the cabinet to be cut to allow for fixing.

Now according to the present invention I provide a stay or strut for hinged lids of gramophones and other cabinets, in which the said stay or strut is provided with a pivotally mounted member or catch adapted to be positively rotated by co-operations with a plurality of cam surfaces or stops provided on or in connection with an oscillating plate or channel with which the strut is adapted to co-operate.

In order that the present invention may be clearly understood and more readily carried into effect, it is hereinafter described with reference to the accompanying drawings, in which:—

Figure 1 is a sectional side elevation illustrating the improved stay or strut applied to a gramophone cabinet and showing the lid thereof supported in a raised position thereby;

Figure 2 is an edge elevation of the improved strut;

Figure 3 is a front elevation of the said strut;

Figure 4 is a detail view showing the relative positions occupied by the parts of the mechanism when the lid of the cabinet is raised;

Figure 5 is a similar detail view showing the relative positions occupied by the parts of the mechanism when the strut is supporting the lid of the cabinet, as in Figure 1;

Figure 6 is a further similar detail view showing the relative positions occupied by the parts of the mechanism when the lid of the cabinet is raised prior to closing same;

Figure 7 is a still further similar detail view showing the relative positions occupied by the parts of the mechanism as the lid of the cabinet is being closed, and

Figure 8 is a substantially similar view to Figure 7 showing the channel through which the strut slides pivotally connected to and supported by a bracket and top plate in place of the side bracket shown in the preceding figures of the drawing.

As shown and referring to the accompanying drawings, it will be seen that the im-

proved automatic support or strut comprises a straight strip 12 of metal or other suitable material which is pivoted at one end at 13 to a fixing plate 14, to be attached to the lid 15. 60 In the particular construction illustrated the fixing plate is formed in two parts hinged together at 16. This enables the fixing to be made to any type or shape of lid, as will be readily understood. The strut 12 slides 65 in two channels of a partly revolving pivoted plate 17 attached, as by a bracket plate 18, to the body of the cabinet 19. The pivot about which the plate 17 turns is indicated by the numeral 20. The two inturned edges 70 21 and 22 of the channels of the plate 17 have, as shown, an irregular or cam formation. Co-operating with the two irregular or cam formations I fit to the other end of the strut 12 an elongated revolving member 23 which is substantially the shape of a rhomboid. This member is held friction tight by a suitable spring washer 24.

In operation the movement to open and support the lid of the cabinet is as follows:—The lid 15 of the cabinet 19 is raised from a closed position, in which the part 23 of the mechanism assumes the position shown in Figures 3 and 8, up to its full extent till the parts assume the position 85 shown in Figure 4 with the member 23 engaged at its upper end with the upper in-turned edge portion 21. Then the lid is slightly lowered till the parts assume the position shown in Figures 1 and 5 with the member 23 resting at its lower pointed end against the shoulder of the inturned portion 22 and the upstanding portion 22^a of the part 17. In this position the lid 15 of the cabinet 19 is supported by the strut 12. In 90 order to close the lid of the cabinet it is necessary to again raise the lid to its full extent till the part 23 is engaged by the part 21, as shown in Figure 6. Then the lid can be closed and on the downward movement 100 the part 23 will be turned round partly by contact with the shoulder 22^a and then by engagement with the inturned part 22, as indicated in a state of transition in Figure 7 and in a completed stage in Figure 8. 105

The shape of the irregular or cam formation of the inturned edges 21, 22, 22^a of the channel and the shape of the elongated rhomboidal-shaped member 23 can be varied retaining the same movements. In 110 some designs of cabinets it is advisable to reverse the support or strut 12, the top end

in this case being fixed to the cabinet 19 and the bottom fixed to the lid 15.

It will be appreciated from the foregoing description that the operation of the 5 strut is quite fool proof and automatic in its action and that the revolving member or catch 23 partakes of a step-by-step anti-clockwise movement, turning through 180 degrees for four strokes, constituting a complete cycle of operations, whilst the channel plate 17 merely oscillates about its pivot.

In some cases and in place of the bracket 18 adapted to be screwed to the inside of a cabinet I may employ a bracket of the 15 kind shown in Figure 8 having a flat horizontal top plate 24 adapted to be held by screws 25 to the motor board of the machine and a depending wing plate or lug 26 to hold the pivot 20 as will be readily 20 understood.

What I claim is:—

1. A supporting strut for hinged lids of cabinets and the like, including a strut proper connected to the lid, a plate supported 25 on the cabinet and slidably receiving the strut, a member pivotally mounted on the strut, and means on the plate to be engaged by said member in successive longitudinal movements of the strut, said means in one 30 upward movement of the strut serving to position the member for interlocking with the plate on the next downward movement to support the strut in elevated position, said means in the next successive upward movement 35 of the strut serving to position the member to cause it to be rotated during an opposing movement of the strut to a position to free it with respect to the plate.

2. A strut for hinged lids of cabinets, including a strut proper connected to the lid, a plate mounted on the cabinet and formed with spaced abutments, and a member pivoted on the strut and operative in successive 45 movements of the strut to first cooperate with one abutment of the plate for positioning the member for locking cooperation with the other abutment and then cooperate with the first abutment for positioning said member to be rotated on further cooperation with 50 the second abutment.

3. A stay or strut for gramophone cabinets or the like, including a strut connected to the lid of the cabinet, a member rotatably mounted on the strut, and a plate fixed to 55 the cabinet proper to slidably receive the

strut, said plate having an upper abutment and a lower stop, the member on the strut being formed to cooperate with the abutment and positioned for locking engagement with the stop to hold the strut in fixed 60 relation to the plate, the said member on subsequent cooperation with the abutment being turned out of cooperative relation with the stop, the new relation of the member causing the stop to turn the member on its 65 pivotal mounting without interfering with the movement of the strut.

4. A strut for gramophone lids, including a strut proper secured to the lid, a plate secured to the gramophone cabinet, an abutment carried on the plate, a stop carried by the plate below the abutment, and a member pivotally mounted on the strut, said member being formed to cooperate with the abutment in the initial upward movement of 75 the strut, to move the member in position to cause one of its edges to engage with the stop on the following limited downward movement of the strut to hold the strut against further downward movement, said 80 member on the succeeding upward movement of the strut engaging the abutment and being operated through said engagement to a position to permit it to be swung on its pivotal mounting in cooperation with the 85 stop on the next downward movement of the strut.

5. A strut for gramophone lids, including a strut proper secured to the lid, a plate pivotally secured to the gramophone cabinet, an abutment carried on the plate, a stop carried by the plate below the abutment, and a member pivotally mounted on the strut, said member being formed to cooperate with the abutment in the initial upward 95 movement of the strut, to move the member in position to cause one of its edges to engage with the stop on the following limited downward movement of the strut to hold the strut against further downward movement, said member on the succeeding upward movement of the strut engaging the abutment and being operated through said engagement to a position to permit it to be swung on its pivotal mounting in cooperation with the 100 stop on the next downward movement of the strut.

In testimony whereof I have hereunto signed my name.

AUBREY LAWRENCE COLLINS.
